Atty.

UNITED STATES PATENT OFFICE.

JOHN B. ROHRER, OF PHILADELPHIA, PENNSYLVANIA.

COMBINED CRIB, CHAIR, AND COMMODE.

SPECIFICATION forming part of Letters Patent No. 276,633, dated May 1, 1883.

Application filed October 14, 1882. (No model.)

To all whom it may concern:

Be it known that I, JOHN B. ROHRER, a citizen of the United States, residing at Frankford, Philadelphia, in the county of Philadelphia and State of Pennsylvania, have invented 5 certain new and useful Improvements in Combined Crib, Chair, and Commode; and I do hereby declare the following to be a full, clear, and exact description of the invention, such as 10 will enable others to make and use the same, reference being had to the accompanying drawings, and to letters or figures of reference marked thereon, which form a part of this specification.

15 Referring to the drawings, Figure 1 is a side view of the device embodying my invention, showing the arrangement of parts when used as a crib. Fig. 2 is a top view thereof. Fig. 3 is a transverse vertical section in the line x 20 x of Fig. 2, showing the grooves or channels. Fig. 4 is a side view of the device when used as a chair. Fig. 5 is a front view thereof. Fig. 6 is a cross-section of Fig. 2 in the line y y . Fig. 7 is perspective view of the bottom 25 rail, showing the bracket, with the pivot and the groove.

Similar letters refer to similar parts throughout the several views.

My invention has for its object the construction, in combination form, of three articles of 30 furniture in a neat, compact, and substantial manner.

Referring again to the drawings, A A represent 35 the framing, of ordinary construction, which form the sides for the crib or sides and handles for the chair, as it is desired to be used.

B represents the commode or seat when the article is used as a chair.

40 When forming a crib the head-board a' , being supplied with legs, forms a support for one end of it. When forming a chair the head-board a' is swung into line with the bottom of the crib a , which, when swung on its pivots or trunnions, rests perpendicular, in which position it also forms the back of the chair.

The supplemental lid or cover b for the commode B, which in itself is of ordinary construction, is used to form the foot-board of the 45 crib.

The two arms or brackets D D, secured to the sides of the commode B, carry pins or trunnions d d at their outer ends, which traverse grooves or channels E E on the inside

5 and near the bottom of the sides A A. These give support to the foot end of the crib, and form the bearings on which to swing the sides, bottom, and head-board which form the back and sides for the chair.

Pins b' b' , on opposite sides of the commode 60 B, fit into recesses or sockets c c , prepared in the ends of the sides A A. These receive the greater portion of the weight of the back when used as a chair and tend to hold all the parts steadily.

The end or head board, a' , when the article is used in crib form, is held firmly perpendicular by small spring-catches h h on the ends 65 of the sides A A, and when liberated swings on the hinges g g against the under side of the crib and forms the head for the back of the chair.

The grooves or channels E E are of a proper length to allow space for a mattress or cushion between the back of the chair and the rear 70 of the commode.

The pins d d , it will be seen, do not pass entirely through the rails or sides, A A, but into channels or grooves, as stated, and as the grooves and pins are upon the inside both are 75 entirely hid from view. Suitable spring-catches are also used to hold the foot-board steadily when using it as a crib.

The artistic manner in which this invention can be made, the small space it occupies, and 80 the three valuable articles of furniture it supplies make it a highly useful and ornamental article.

Having thus described my invention, what I 85 claim as new, and desire to secure by Letters Patent, is—

1. In the combined crib, chair, and commode, as described, the combination of the sides A A and folding head-board a' with commode B, and supplemental lid or cover b , 90 arranged and operating substantially as specified.

2. In the combined crib, chair, and commode, as described, the combination of the commode B and the brackets D D with the trunnions d d , and the sides A A with the grooves or channels E E, all arranged and operating as set forth.

JOHN B. ROHRER.
